DESCRIPTION

FIG. 1 is a front perspective view of the coin sorting and calculating machine of the present invention;

FIG. 2 is a lower front perspective view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a lower rear perspective view thereof; and,

FIG. 9 is a rear view thereof.

FIGS. 3-7 and 9 are drawn on a reduced scale.
